EMIL C. LOETSCHER, OF DUBUQUE, IOWA.

MULTIPLE REFRIGERATING APPARATUS.

1,222,642.

Specification of Letters Patent. Patented Apr. 17, 1917.

Application filed April 9, 1915. Serial No. 20,128.

To all whom it may concern:

Be it known that I, EMIL C. LOETSCHER, a citizen of the United States, residing at Dubuque, in the county of Dubuque and State of Iowa, have invented certain new and useful Improvements in Multiple Refrigerating Apparatus, of which the following is a specification.

The refrigerating apparatus herein shown is only a part of a refrigerating system since the particular point of novelty of the invention to be herein described resides in the means for operating two or more refrigerating members from one refrigerating machine.

The apparatus shown is adapted to be connected to a refrigerating machine of the absorption type, such as shown in my application, Sr. No. 16,551 filed March 24, 1915.

20 The drawing illustrates various modifications for accomplishing the same result.

Figure 1 is a diagrammatic view, with parts in section, showing the preferred arrangement of the parts.

25 Fig. 2 is a view similar to Fig. 1 showing a slightly modified arrangement of parts.

Fig. 3 is a view similar to Fig. 1 wherein three refrigerating members are shown.

20 Fig. 4 is a view similar to Fig. 1 showing a further modification.

Fig. 5 is a side elevational view of my improved refrigerating apparatus with parts in section.

Referring now more particularly to the drawing, the refrigerators 10 and 11 may be of any desired form and are herein shown as one located above the other, to illustrate the fact that the refrigerator 10 may be upon the first floor of a building and the refrigerator 11 may be upon the fifth floor of a building or, in fact, at any point in the building above the refrigerator 10. The refrigerating member 12 for the refrigerator 10 and the refrigerating member 13 for the refrigerator 11 have heretofore been more particularly described in my application for improvements in refrigerating apparatus filed March 24, 1915, Sr. No. 16,551 and need not be herein further described.

50 The refrigerating member 12 comprises a chamber 14 similar to the chamber 15 in the refrigerating member 13. The pipe 16 leads to the rectifying coil of a refrigerating machine of the absorption type. The pipe

17 leads to the condensing member of the 55 refrigerating machine. The coil 18 is submerged in a brine-tank 19 and both of its ends are in communication with the chamber 14. The function of the coil is to evaporate the refrigerant in the refrigerating 60 member 12.

The coil 20 submerged in the brine-tank 21 performs the same function as the coil 18.

A pipe 22, having a relatively small interior diameter, is connected to the chamber 65 14, preferably near the bottom thereof, and to the chamber 15 preferably near the top thereof. A pipe 23 is connected to pipe 16 at one end and has its other end terminating within the chamber 15. The refrigerating 70 systems, which the apparatus herein specifically identified is adapted to form part of, comprise (Fig. 5) a generator-absorber 46, which is provided with a vapor conveying member 47 that extends upwardly 75 from the generator-absorber and is then bent upon itself with its discharge end entering the equalizing member 48. An absorption pipe 49 disposed near the bottom of the generator-absorber is connected to 80 the equalizing member by the extension pipe 50, the upper end of the extension pipe projecting beyond the lower end of the vapor-conveying member 47 so as to form an overflow pipe for the liquid in the equalizing 85 member.

A rectifying coil 51 has one end in communication with the equalizing chamber 48 with the coils thereof located within the condensing tank 52. Within the generator-absorber is a cooling coil 53 the upper end 90 of which is located in the condensing tank at a point slightly below the highest overflow level. A check valve 54 is located in the upwardly extending portion of the cooling coil 53.

A cooling medium, such as water, is supplied to tank 52 by means of a water supply pipe 55. The condensing chamber 56 is provided with a single inlet and outlet communicating member 57 that forms part of the pipe 17, while the rectifying coil 15 is connected to pipe 16. Thermostatic means are employed for intermittently applying and shutting off the heating agent, designated as a whole by the numeral 58 and herein shown as electrically operated through the medium of the electrical energy received

through the circuit formed by the wires 58 and 59 that lead to any suitable source of electrical energy.

During the process of generation the gas at high pressure passes from the rectifying member through the pipe 16 to the refrigerating member 12 and from the refrigerating member into the pipe 17 and through said pipe to the condenser of the refrigerating apparatus.

When the absorber of the apparatus is cooled the pressure in the absorber, as well as in the pipe 16, is reduced or is at low pressure compared with the pressure in the generator-absorber when the same is heated.

As a consequence of the reduction in pressure, the liquid within the condenser of the refrigerating apparatus is transferred into the refrigerating member, filling it to the level as indicated at (A). The pipe 22, opening into the chamber 14 at a point near the bottom thereof, is also filled with refrigerant to approximately the same level as the level of the refrigerant within the chamber 14.

The refrigerant now evaporates in the chamber 14 and also in the pipe 22. As the pipe 22 is of comparatively small diameter, the liquid therein will form alternate layers or slugs of liquid and evaporated refrigerant. Under this evaporating influence the slugs of liquid will rise in the pipe 22, being impelled forward partially by the force of the liquid pressure in the chamber 14, which is greater than the pressure of the alternate layers or slugs of liquid and gas in the pipe 22, and partially by the expansive force of the evaporating refrigerant itself, until a portion of the liquid is deposited in the chamber 15.

This process is continued as long as there is any liquid in the chamber 14, and of such a height as to surround the lower end of the pipe 22. As the pipe 23 is in communication with the pipe 16, the pressure within the chamber 15 is practically the same as within the chamber 14 and the refrigerant in each of these chambers will evaporate in proportion to the amount of heat introduced through the coils 18 and 20.

In the apparatus shown, in Fig. 2, the parts bearing reference numerals corresponding to the reference numerals applied to Fig. 1, perform similar functions.

The chambers 14 and 15 in this modification are in communication with each other through the medium of the pipe 22^a which is so connected to the chamber 14 that a portion of the refrigerant therein will flow to the chamber 15 by gravity, instead of being forced upward through the pipe 22 as heretofore described. In this arrangement however, it is necessary to have the chamber 15 at a lower level than the chamber 14 so that a gravity flow will be obtained. Subsequent

evaporation in both refrigerating members takes place as heretofore described. In Fig. 3 I have shown a system wherein two or more refrigerating members may be connected to a single machine.

The refrigerating members or chambers 24, 25 and 26 are similar in function and operation to the chambers 14 and 15 within the refrigerating members 12 and 13. The pipe 16 which is connected to the rectifying coil of the refrigerating apparatus, enters the chamber 26, terminating at the level indicated at (e). The pipe 16^a has one end terminating within the chamber 26 near the top wall and its other end projecting into the chamber 25, terminating at the level indicated at (f). The pipe 16^b has one end terminating within the chamber 25 near the top wall and its other end entering the chamber 24 and terminating at the level indicated at (g).

During the generating process the anhydrous gas passes through the pipe 16 into chamber 26, thence through the pipe 16^a into the chamber 25 and thence through the pipe 16^b into the chamber 24 and finally into the condensing member of the refrigerating machine through the pipe 17.

When the absorber of the apparatus is cooled, the pressure in pipe 16 is reduced causing a corresponding reduction in pressure in the refrigerating member 26, the pipe 16^a, refrigerating member 25, the pipe 16^b and refrigerating member 24. As a result of this reduction in pressure the liquid from the condenser is transferred through the pipe 17 into the refrigerating member or chamber 24 filling it to the level as indicated at (a). Since pipe 16^b is the only outlet for the liquid within the chamber 24, and as the pressure within this chamber is greater than the pressure within the tube 16^b, all of the liquid in the chamber 24 above the lower end of the tube 16^b, is forced upward into said tube and deposited in the chamber 25, filling it to the level indicated at (b). The liquid thus deposited in the chamber 25 will be transferred to the chamber 26 and into as many chambers thereafter as the system may be provided with, assuming, of course, that there is a sufficient amount of refrigerant within the apparatus to fill the various chambers to the proper level in order to obtain the necessary overflow.

When these chambers have been filled with liquid, as described, the process of evaporation and refrigeration continues until all of the liquid therein has been evaporated.

In Fig. 4 I have shown a system of connecting one or more refrigerating members with a refrigerating machine using expansion valves for each refrigerating member.

The refrigerating coils 27 and 28 are connected to the chambers 29 and 29^a. These

chambers 29 and 29^a are in communication with the pipe 16 that leads to the rectifier of the refrigerating apparatus. One end of each coil 27 and 28 is enlarged as indicated at 30 and 30^a for receiving floats 31 and 31^a. The upper ends of said floats are provided with wires 32 and 32^a respectively. The pipes 33 and 33^a are in communication with the chambers 29 and 29^a respectively and their upper ends carry expansion valves 34 and 34^a. The expansion valve 34 comprises an outer casing 35, a cap 36, a filtering medium 37, preferably of porous stone, and a ball check valve 38. The expansion valves 34 and 34^a are each provided with a partition 39 and each partition is provided with an orifice 39^a in axial alinement with the wires 32 and 32^a carried by the floats 31 and 31^a. The function of each wire is to restrict the flow of the refrigerant through the orifices 39^a, when the coils 27 and 28 are filled to a certain level, whereby when the flow of refrigerant is checked, expansion of the gases will take place within the coils. The pipe 40 serves as the communicating means between the valve 34 and the pipe 17. The pipe 17 is in direct communication with the expansion valve 34^a.

An extension pipe 41 is connected to the pipe 17 and partially surrounding the lower end thereof is a thermostatic member 42, one end of which is secured to the pipe 41 and its free end moves into and out of contact with the contact point 43. The wires 44 and 45 connect the thermostatic member to the electrical circuit employed in refrigerating apparatus such as shown and described in my application, Serial Number 16,551 of the series of 1915.

The operation of the apparatus as shown in Fig. 4, is as follows: Assuming that the process of generation is going on, the gas passes from the rectifier through the pipe 16 into the chambers 29 and 29^a. From these chambers it passes up through the tubes 33 and 33^a through the valves 34 and 34^a and thence into the pipe 17 to the condenser, at which point the refrigerant gas is condensed to a liquid.

Now assuming that the process of generation has been terminated and the absorption process has begun, the liquid in the condenser is forced into the pipe 17 and through the valves 34 and 34^a into the chambers 29 and 29^a, thus filling the refrigerating coils 27 and 28. As soon as the refrigerating coils are filled, the floats 31 and 31^a will rise, whereupon the wires 32 and 32^a will enter the orifices 39^a and thus restrict the flow of the refrigerant. As the refrigerant evaporates in the coils 27 and 28, the floats will fall and thus a constant level of refrigerant in the coils 27 and 28 will be maintained until all of the refrigerant in the condenser

of the machine has passed through the valves 34 and 34^a.

As the pipe 41 is in communication with the pipe 17, a small quantity of refrigerant will be necessarily trapped therein. When the liquid in pipe 17 has become exhausted, the small quantity of liquid in the pipe 41 begins to evaporate, causing a reduction in temperature, which change of temperature causes the thermostatic member to move toward the contact point 34 until it strikes the same, thus closing the electric circuit and starting another cycle of operation. It is, of course, desirable to place the pipe 41 with its thermostatic member at a point substantially midway between any two refrigerating coils of the system so that the thermostatic member will not be affected by either refrigerating member, and will thus start a new cycle of operation when both refrigerating members are in substantially the same condition.

Having now described my invention, I claim:

1. In refrigerating apparatus of the absorption type comprising a generator-absorber and a condenser, the combination therewith of a main refrigerating member, means for introducing a refrigerant into said main refrigerating member under generator pressure, an auxiliary refrigerating member, communicating means between said main and auxiliary refrigerating members, means for conveying the refrigerant to said auxiliary refrigerating member under reduced pressure and communicating means between said auxiliary communicating means and said reduced pressure communicating means.

2. In refrigerating apparatus of the absorption type comprising a generator-absorber and a condenser, the combination therewith of refrigerant distributing members having different pressures, a plurality of refrigerant members one of which is directly connected to the high pressure communicating member and communicating means between said refrigerant member and the low pressure communicating member.

3. In refrigerating apparatus of the absorption type and provided with a generator-absorber and a condenser, the combination therewith of a main refrigerating member and an auxiliary refrigerating member, a high pressure refrigerating distributing member connected to said main refrigerating member and a connection between said main refrigerating member and said auxiliary refrigerating member, said auxiliary refrigerating member being in communication with the absorber of the apparatus.

4. In refrigerating apparatus of the absorption type and provided with a generator-absorber and a condenser, the combination therewith of a main refrigerating mem-

ber and an auxiliary refrigerating member, a high pressure refrigerating distributing member connected to said main refrigerating member and a connection between said 5 main refrigerating member and said auxiliary refrigerating member, said auxiliary refrigerating member being in communication with the generator-absorber of the apparatus and said communicating member between 10 said auxiliary and main refrigerating members extending into said main refrigerating member and below the normal level of the liquid therein.

5. In refrigerating apparatus of the absorption type comprising a generator-ab- 15

sorber and a condenser, the combination therewith of a low pressure and a high pressure refrigerant distributing members, communicating means between said members for conveying a refrigerant material to the 20 same, and thermostatic means connected to said communicating means between said distributing members, and operated by the temperature of the refrigerant in said communicating means.

EMIL C. LOETSCHER.
